ELECTRICIAN'S TOOL

Richard V. Tays, Coral Gables, Fla.

Application January 19, 1938, Serial No. 185,779

3 Claims.

(CL. 7—1)

This invention relates to tools particularly designed for use by electricians and an object of the invention is to provide a tool so constructed that the same may be used both as a tape puller and also as a tape straightener.

As is well-known electricians have resort to what is known as a "fish tape puller," that is a tool particularly useful for pulling a steel fish tape and electric wires connected thereto, through an electric conduit. In accordance with the present invention my improved tape puller may also be used in an efficient manner for straightening the tape, it being understood that the tape has a tendency to coil. With my tool the coiled tape can be quickly and easily straightened.

The invention together with its objects and advantages will be best understood from a study of the following description taken in connection with the accompanying drawing wherein:

Figure 1 is a side elevational view of the tool showing the same in a position for use as a "puller,"

Figure 2 is a fragmentary edge elevational view of the tool, and

Figure 3 is a fragmentary side elevational view of the tool showing the parts thereof in position when the tool is being used as a "straightener."

Figure 4 is a reverse view of the structure shown in Figure 3, but with the handles at approximately right angles to each other.

Referring to the drawing by reference numerals it will be seen that in the preferred embodiment thereof the tool comprises a pair of handles 5, 6 having working ends 7 and 8 respectively.

The working end 7 of the handle 5 comprises a shank portion merging into a substantially circular head 9 and an integral guard member 10 disposed in spaced parallelism with the said shank and terminating short of the head 9 of the shank as shown in Figure 2 so as to accommodate between the shank and the guard 10 the tape 11. Between the shank and guard 10 the end 7 is provided with a gripping jaw or formation 12 which is rounded off at one end thereof as at 13 to form a curved straightening surface as and for a purpose which will presently present itself.

The working end 8 of handle 6 extends from the handle at the longitudinal center thereof, as shown in Figure 2, and presents an enlarged cam-like working jaw 14 pivoted to the head 9 as at 15 and having its free end working between the shank and guard 10 of handle 5 so as to cooperate with the jaw 12 of the end 7 for clamping

the tape 11 therebetween as shown in Figure 1 when the tool is to be used for pulling the tape through a conduit, and also for cooperation with the curved straightening surface 13 when the handles are in the angular position shown in Figure 3, and in which case the tool is being used for straightening the tape.

Referring to the several figures, and particularly to Figure 4, it will be noticed that, while the cam-like member 14 is pivoted at 15, the outer edge thereof is not concentric with the pin 15. The point 16, which is the gripping part (Figure 1) is most distant from the pivot 15; while part 18 is much nearer the pivot 15, and leaves a space between this part and the end of the guard 10, to form an entrance or gateway for the tape.

When the parts are in the position shown in Figure 1, the guard 10 extends over the cam point 16 of the cam-like member 14, thus enclosing the fish tape so that it can not pass out of the tool. The same is true when the parts are in the position shown in Figure 3, which is the straightening position; here again, the guard 10 extends over the tape 11, and so prevents the escape of the tape while being straightened. But when the handles are in some intermediate position, as shown in Figure 4, the part 18 of the cam-like member 14 leaves an opening or gateway between the same and the end of the guard 10; therefore, when the parts are in this position, the fish tape may be either introduced into or removed from the implement at will. Thus, the fish tape is fully guarded against displacement, both when being pulled, as in Figure 1, and when being straightened, as in Figure 3; but when the handles are brought to the position shown in Figure 4, the tape can be at once introduced or withdrawn from engagement in the tool at the will of the operator.

By providing the rounded curved straightening surface 13 for the jaw 12 the handles 5 and 6 are permitted to be moved into acute angular relation as shown in Figure 3 to the end that the handles may be grasped by one hand as the tape is being held by the other during the straightening operation.

In using the tool for straightening the tape the tool is engaged with the tape as shown in Figure 3, and the tape pulled through the tool between the part 18 of the cam-like working jaw 14 and the straightening surface 13 of the gripping jaw 12, thus causing the tape to straighten out.

Also by permitting the handles to move to such close position relative to one another as suggested in Figure 3 the tool may be readily carried

in the pocket by the user and in this connection may be so placed within a side pocket of the trousers or overalls as to let one of the handles extend into the pocket and the other handle extend outwardly of the pocket permitting the user to readily engage the tool and withdraw the same from the pocket.

In using the implement as a straightener, as shown in Figure 3, the fish tape is inserted so that the curved edge 13 cooperates with one side thereof and the top part 18 of the cam-like jaw 14 with the other side thereof. At the same time the tape is necessarily positioned behind the guard 10, as shown particularly in Figure 3, so that it can not slip out of position while being straightened. By drawing the tape through the tool, or by moving the tool over the tape, the curl will be taken out, and the tape straightened. The effect of the tool on the tape can be varied by varying the pressure on the handles. The closer the handles are pressed together, the greater the effect on the tape, and vice versa.

Thus the part 18 of the cam-like member 14 really has two functions; first, it serves to form an opening or gateway behind the guard 10; and, second, it constitutes one of the two elements used to straighten the tape.

It is thought that a clear understanding of the construction, utility and advantages of a tool of this character which has been designed to meet the needs of the trade, will be had without a further description thereof.

Having thus described the invention what is claimed as new is:

35. 1. A tool of the character described comprising a pair of handle members, one of said members at one end being bifurcated so as to form parallel elements of unequal length with a gripping jaw and a curved straightening surface between them, the longer of the two elements being provided with a pivotal connection, and the shorter of the two elements extending beyond the gripping jaw and the straightening surface, and the

other of the said handle members being pivotally connected with the first mentioned handle member and having a cam-like end, one part thereof being adapted to cooperate with the gripping jaw of the first mentioned handle member when the parts are in tape pulling position, and another part thereof being adapted to cooperate with the straightening surface of the first mentioned handle member when the parts are in tape straightening position.

2. A tool for straightening fish tapes comprising a pair of handle members, one of said members at one end being bifurcated so as to form parallel elements of unequal length with a curved straightening surface between them, the longer of the parallel elements being provided with a pivotal connection, and the shorter of the two elements extending beyond the straightening surface to protect the fish tape, and the other of said handle members being pivotally connected to the first mentioned handle member and having a cam-like surface for cooperation with the straightening surface of the first mentioned handle member, the straightening surface being adapted to engage one side of the fish tape and the cam-like surface being adapted to engage the opposite side of the fish tape, the points of engagement being spaced apart longitudinally of the tape.

3. A tool of the character described comprising a pair of handle members, one of said members being provided with a gripping surface and a curved straightening surface and the other member having a cooperating gripping surface and a cooperating cam-like surface, and means for so pivotally connecting the two members that they may be brought into approximate alignment to grip the tape, and into close angular relation to permit the straightening surface and the cam-like surface to cooperate to straighten the tape as the tape and tool are moved relatively to each other.
